BOX PILING

Adolf Borberg, Short Hills, N. J., assignor to
 Dortmund Hoerder Huettenverein Aktien-
 gesellschaft, Dortmund, Germany, a corpora-
 tion of Germany

Application January 5, 1934, Serial No. 705,363

5 Claims. (Cl. 61—61)

This invention relates in general to box piling of the sheet metal type, and involves in principle the formation of box piling units from pairs of standard arched web half wave sheet metal piling of the interlock type.

In the formation of the box piling, in accordance with this invention, various well-known types and depths of such arched or deep arched web sections may be employed, and the term "arched" is to be understood as embracing all of these. The sections of each pair comprising a unit may be of equal or of unequal depths, according to preference. The edges of the respective sections are each provided with one or more interlock members of any approved type. In the assembly of the two sections to form a box unit, one section is disposed with its concave face toward the concave face of the other section, and the two sections are permanently and rigidly secured together, as for example by welding their adjacent edges or by other approved method.

Several examples of the principle involved, and the method of joining a number of such box piles to form a wall, bulkhead or other structure, are shown in the accompanying drawing, in which

Figure 1 is a cross-section of three units of box piling constructed from pairs of standard deep arched double interlock piling of unequal depths of arch.

Figure 2 is a similar view illustrating the joining of two such box piling units by one or more deep arch piles.

Figure 3 is a similar view showing the construction of two box pile sections of equal depth of arch with an intervening connecting box pile constructed of standard sections of unequal depths of arch.

Figure 4 is a similar view of two box pile units constructed of two standard deep arched pile sections of equal depth, the two box units being joined by, for example, one intervening deep arch pile of greater depth; and

Figure 5 is a similar view of two box pile units constructed of pile sections of equal depth of arch and the connection of the two box units by one or more standard straight web interlock section.

Referring to Figures 1 and 2, each box unit is in this example composed of two deep arched web half wave piles, one of which is deeper arched and the other of which is more shallow. The deep arched section comprises the web 10, flanges 11, 12, and immediately adjacent to said

flanges the interlock guard members 13, 14 extending along the respective edges of the section and adjacent thereto the interlock hook members 15, 16. The shallow arched web section comprises the web portion 17, the flanges 18, 19, and immediately adjacent to said flanges the interlock guard members 20, 21 and the interlock hook members 22, 23. Three such box units connected together are illustrated in Figure 1, whereas in Figure 2 I have shown by way of example two such box members connected together by an intervening deep arch section having a web portion 24, flanges 25, 26, interlock guard members 27, 28 extending along the respective edges thereof and adjacent thereto the interlock hook members 29, 30. The box sections are illustrated as rigidly and permanently secured together by lines of welding a, b, which are intended to represent any suitable type of connection by which the two members of the pair are to all intents and purpose converted into an inseparable unit which may be driven and pulled as a single pile. It is contemplated that the joining of the two members of the pair may be effected at any time prior to driving, either on the job or prior to delivery at the job.

The distinction of this form of box pile—and the other forms shown and to be described later—over the prior art suggestions of forming box piles is that only adjacent "half wave" sections are interlocked by their interlock elements, such as for instance the half wave sections 10, 10, 10 in Fig. 1, being interlocked at 15 and 16. Besides, each arched web section which is paired with and rigidly attached to another arched section (for instance 10 and 17) is so attached entirely independent from the interlock elements of the next adjoining box pile sections. Furthermore, these rigidly secured edges of each box pile are transversely displaced from the axis on which the box pile interlocks with an adjacent pile, and also from the neutral axis of the wall. For instance, in Fig. 1 the two rigid joints a are displaced transversely from the axis which runs through the interlocked elements 15, 15 and 16, 16 and they are also displaced transversely from the neutral axis of the wall which runs in that case nearly midway between the joints a. A similar condition exists in the other modifications, to be described later. The result of this arrangement is that the connection between two box piles is greatly strengthened by the transversely superposed or adjacent interlock members, which extend substantial distances to either side of the neutral wall axis

and hence give rise to a greatly increased wall section modulus at the joints between the boxes.

The interlocks illustrated are intended to be conventional and to represent any standard form. In the same way the piling sections employed are of standard half wave construction, so that the expense of special rolling is avoided, and the box units may be connected with any of the stock or standard units of similar type of interlock and suitable dimensions. The three units shown in Figure 1 are of the same over-all depth, the intermediate unit being reversed with respect to the two outer units so as to maintain the two wall faces in substantial alignment. The same box units are illustrated in Figure 2, and interconnected by a deep arched web section of the same depth as the deep arched web section employed in the construction of the box units, whereby the continuity of the wall line is substantially maintained on one side only. Any of the units may obviously be of any desired width within the standard stock dimensions of such sheet metal piling.

In Figure 3 a pair of deep arched web sections 31, 32, similar in construction to those described in connection with Figures 1 and 2, are employed for each of the two outer box units and similarly joined permanently together, but in this example the two deep arched sections are of equal depth. Where it is desired to maintain wall face alignment, these box units may be connected by a box unit composed of the deep arched web section 33 and the shallow arched web section 34. It will be noted that the section 33 is deeper than the sections 31 and 32, whereas the section 34 is much more shallow than sections 31 and 32, as a result of which the wall line on either face is substantially maintained. In Figure 4 the construction and arrangement are the same, with the exception that the deep arched web section 33 is in this instance not joined to a shallow arched web section 34, to form a box, so that the wall line is more or less maintained on one face but interrupted on the other.

A still further example of connecting the box piles by intervening standard units is illustrated in Figure 5, in which the box pile units composed of the deep arched sections 31, 32, permanently joined as previously described, are shown connected by the intervening straight web section 35, it being understood that in this instance two such straight web sections 35 may be interposed between the two box sections as two pairs of hook members are available. Furthermore, straight web sections, such as illustrated at 35, may obviously be employed to connect box type units, whether the sections of which such units are constructed are of equal depth, or of unequal depths such as illustrated, for example, in Figures 1, 2 and 3.

The examples chosen for illustration are intended merely to suggest some of the many ways in which box piles of this type and construction may be joined with each other or with other types of pile sections. Furthermore, a straight web section may be substituted for one of the two arched web sections in the construction of a box pile unit under the principle set forth, but while such a construction may be regarded as an equivalent construction within the broad scope of the invention herein claimed, its occur-

rence would be very infrequent in practical use on account of the increasing difficulties of driving as the structure departs further from the symmetrical form. In practice, the formation of the box unit of two arched web sections of equal depth is usually preferred to any of the unsymmetrical forms.

I claim:—

1. In combination, a series of three or more box pile units, each of said units comprising a pair of half wave arched web pile sections of unequal depth, each section having along each of its edges an interlock member, the pile sections of each pair being rigidly secured together along their edges with their concave faces inward and the two edges of one section adjacent the two edges of the other section to form a box, said series of box pile units being interconnected with their deeper arched sections alternately disposed with respect to the series axis. 15

2. A box pile wall composed of a plurality of interlocked box piles, each pile comprising a pair of half-wave arched web pile sections, each section having along each of its edges an interlock member, said pair of pile sections being rigidly secured together along their interlock members with their concave web faces inward to form a box pile, adjacent box piles having their respective rigidly secured edges transversely spaced from the interlock axis and the neutral axis of the wall. 20

3. A box pile wall composed of a plurality of interlocked box piles, each pile comprising a pair of half-wave arched web pile sections, each section having along each of its edges an interlock member, said pair of pile sections being of unequal depth and being rigidly secured together along their interlock members with their concave web faces inward to form a box pile, adjacent box piles having their respective rigidly secured edges transversely spaced from the interlock axis and the neutral axis of the wall. 25

4. A box pile wall composed of a plurality of interlocked box piles, each pile comprising a pair of half-wave arched web pile sections, each section having along each of its edges an interlock member, said pair of pile sections being of equal depth and being rigidly secured together along their interlock members with their concave web faces inward to form a box pile, adjacent box piles having their respective rigidly secured edges transversely spaced from the interlock axis and the neutral axis of the wall. 30

5. A box pile wall composed of a plurality of interlocked box piles, each pile comprising a pair of half-wave arched web pile sections, each section having along each of its edges an interlock member, said pair of pile sections being rigidly secured together along their interlock members with their concave web faces inward to form a box pile, adjacent box piles having their respective rigidly secured edges transversely spaced from the interlock axis and the neutral axis of the wall, some of said box piles being composed of arched web pile sections of equal depth and some being composed of arched web sections of greater and less depth than said equal depth sections, those of one type alternating with those of the other type. 35

ADOLF BORBERG.
